Atty.

UNITED STATES PATENT OFFICE.

FRANK G. BIELEFELD, OF CHICAGO, ILLINOIS, ASSIGNOR TO THE ADAMS & WESTLAKE MANUFACTURING COMPANY OF MICHIGAN, OF SAME PLACE.

GAS-BURNER.

SPECIFICATION forming part of Letters Patent No. 365,899, dated July 5, 1887.

Application filed May 12, 1885. Serial No. 165,191. (No model.)

To all whom it may concern:

Be it known that I, FRANK G. BIELEFELD, of Chicago, in the county of Cook and State of Illinois, have invented certain new and useful Improvements in Gas-Burners, of which the following is a specification.

In the accompanying drawings, Figure 1 is a top view. Fig. 2 is a longitudinal section. Figs. 3 and 6, 4 and 7, and 5 and 8 represent details of the invention, hereinafter described.

Similar letters of reference indicate similar parts in the respective figures.

The object of this invention is to effect an even distribution of atmospheric air to the burner and a proper admixture of the air and gas, whereby an exceedingly steady and hot flame is produced.

A is a horizontal Bunsen tube, communicating at one end with the gas-tube A', which is provided with a cock, a, screwed into a bar, a', forming a part of the Bunsen tube and extending across its open end. The air enters the Bunsen tube above the bar a' at a'', and underneath through the opening b. The other end of the Bunsen tube is provided with a burner, B. The upper wall or top of the Bunsen tube is provided with a circular aperture, d, and a projection or ring, e, surrounding said aperture. A hollow inverted cone, f, (shown detached and enlarged in Figs. 3 and 6,) is provided with a shoulder, f', which fits over the projection e. The cone is provided with a flange, g. Upon this flange rests the ring h, (shown detached and enlarged in Figs. 4 and 7,) said ring being provided with lugs or feet h', which rest upon the flange, and with projections i on the opposite side. A cap, k, rests upon the projections i, said cap being shown detached and enlarged in Figs. 5 and 8. The lower or under portion, l, of the cap is cylindrical, and provided with lateral apertures m, leading from its interior out into the space ex-

isting between the top of the ring h and the under side of the flange k' of the cap. The part l of the cap is centrally perforated, and, with the cone f, is secured to the Bunsen tube by means of a screw-bolt, n, which screws into the boss upon the under side of the Bunsen tube.

In operation gas is admitted to the Bunsen tube through the aperture p of the cock a', the air entering through the openings a'' and b. The gas and air in a mixed state pass up through the inverted cone f and impinge against the conical under side of the part l of the cap k, whence the greater portion is deflected laterally through the spaces formed by the ring h, the under side, k', of the cap k, and the upper side of the flange g, a double flame being thus produced all around the side of the burner. At the same time a certain amount of the mixed air and gas escapes through the apertures m m in the crown of the cap, and a flame is thus produced in the central part of the cap k, immediately above the head of the bolt n. By this means a most intense heat is effected without being unduly concentrated at one point, so as to injure the vessel with which it may come in contact.

Having described my invention, I claim—

The lower cone, f, having the flange g, the cap k, provided with a cylindrical center having lateral perforations m, and the intermediate ring, h, having the lower projections, h', and upper projections, i, the said several parts being relatively arranged as described, combined with a Bunsen tube, and the securing-bolt n, substantially as described.

In testimony whereof I hereunto set my hand and seal.

FRANK G. BIELEFELD. [L. S.]
